APPARATUS FOR CONTINUOUSLY APPLYING LIQUIDS TO THE UNDERSIDE OF SHEET MATERIAL

Arthur S. Gregory, Longview, Wash., assignor to Weyerhaeuser Timber Company, Tacoma, Wash., a corporation of Washington

Application December 30, 1953, Serial No. 401,351

2 Claims. (Cl. 118—315)

This invention relates to method and apparatus for continuously applying liquids to the underside of sheet material, particularly to the underside of felted fibrous mats preliminary to pressing them in the manufacture of fiberboard.

For various applications it frequently is necessary that a liquid be applied to the surface or surfaces of sheet materials. For example, in the preparation of hardboard it may be desirable to spray the surfaces of a felted lignocellulose fiber mat with a predetermined quantity of water. Then when the mat is transferred to a hot press, the water has the desirable effect of plasticizing the fibers adjacent the surface so that they conform to the contour of the press caul plate with which they are in contact. This imparts a smooth surface to the finished board.

It also may be advantageous to apply a liquid other than water to the surfaces of such mats. In the manufacture of hardboard, for example, there may be thus applied aqueous solutions, suspensions or emulsions of solid or liquid materials such as thermosetting resinous adhesives, or inorganic salts used as fire retardants, or organic or inorganic solid materials employed as mold-proofing agents. Still further, it may be desired to apply to the mat surface solutions of solid materials in non-aqueous solvents such as the hydrocarbon solvents, or the lower aliphatic alcohols; or mixtures of liquids in emulsion form; or suspensions of solids in liquids, or molten solids, or thixotropic colloidal systems.

The continuous application of these and other liquid systems to the top surface of sheets, e. g. felted mats of lignocellulose fiber, usually is accomplished easily by well known procedures, such as spraying, transfer from a roll, or doctoring. However, applying liquids to their under surfaces as frequently as desirable is impractical or even impossible of attainment because of several factors.

If it is attempted to coat the under surface by first inverting the mat, an additional processing operation obviously is required. In addition, where a felted fibrous mat is the subject matter of the operation, it is impossible to invert it without disintegrating it, or disarranging the fibers of which it is composed.

Such disarrangement of the fibers may well be fatal to the successful application of the mat in the production of consolidated products. During the preparation of the mat, great care is exercised to distribute the fibers evenly so that the mat is of uniform thickness. Also, care should be taken to intertwine the fibers and orient them in random arrangement to obtain a consolidated product of maximum strength. Accordingly, any disarrangement of the fibers may make the thickness of the mat non-uniform so that a board of non-uniform density is obtained. Also, it may disentangle the fibers, destroying the fiber interlock, so that the consolidated product delaminates comparatively readily, or is of impaired strength.

Disarranging the fibers in the mats prior to pressing also has the disadvantageous effect of producing a rough

2

surface, or one which is not uniform in color. Accordingly, it is essential for many purposes that the fibers in the body of the mat be not disturbed and that those on the surface of the mat be disturbed as little as possible. Hence, inverting the mat is an undesirable procedure, as is sliding it over a surface once the fibers have been moistened, since, in the latter case, the fibers tend to stick to the moistened surface.

It now has been discovered that the foregoing difficulties may be overcome and even relatively non-coherent sheets sprayed on their under surfaces with liquid materials by the use of method and apparatus which do not invert the sheet and which do not move it relative to the supporting surface after it has been moistened. Broadly stated, this method comprises supporting the sheet on a first supporting member moving at a predetermined velocity and transferring the sheet to a second supporting member stationed downstream from the first supporting member and moving in the same direction at the same velocity. At the transfer point between the two supporting members there exists a gap at which an area of the sheet undersurface is exposed. Liquid then is applied to the under surface at this transfer point.

The apparatus for accomplishing the foregoing method comprises a member for supporting the sheet, means for moving it across the supporting member, and conveying means a spaced distance below the supporting member and extending outwardly on the outfeed side of the apparatus for conveying the sheet away.

30 Stationed opposite the space between the supporting member and the conveying means is a liquid applying means for applying liquid to the exposed under surface of the sheet as it transfers from the support member to the conveying member. At this junction, the liquid may be applied uniformly to the under surface without danger of disintegrating the sheet or of disarranging the fibers of which it may be composed.

This apparatus is described in detail below with particular reference to the drawings wherein:

40 Figure 1 is a schematic view in side elevation of apparatus for forming a mat from fibrous material, including the means described herein for applying liquids to the under surface of the formed mat;

45 Figure 2 is an enlarged, detail, sectional view illustrating the construction and operation of the herein described apparatus for applying liquid to the underside of the mat; and

50 Figure 3 is a fragmentary view, partly in section, taken along the line 3—3 of Figure 2.

55 As is illustrated in the drawings, the apparatus for continuously applying liquids to the underside of moving sheets which comprises the subject matter of the present invention may be employed to advantage in conjunction with apparatus for felting lignocellulose fiber into a mat, cutting the mat into sections, and introducing the sections into a heated press for consolidating them. Thus in the illustrated embodiment, wood or other fibers may be introduced into a foraminous felting head 10 under a positive air pressure. The felting head is provided with a bladed wheel 12 which agitates the fibers within the head, passing them in dispersed form through the openings in the bottom of the head.

60 The fibers travel downwardly into a felting area defined and partially enclosed by shield 14. They then are formed into a continuous mat on a felting member such as the endless Fourdrinier wire 16 at the point where it passes over a suction box 18 maintained under a negative air pressure by means of fan 20, and stationed below and in substantial registration with shield 14.

65 In this manner the fibers are driven into a uniform mat or sheet 21 on the Fourdrinier wire. The mat first passes

beneath a press roll 22 which effects its partial consolidation. It then passes the cut-off saws, represented schematically at 24, which cut it into sections of substantially equal length.

The mat sections pass onto a downwardly inclined transfer belt 26 driven in the outfeed direction at a rate substantially equal to the rate of travel of Fourdrinier wire 16. This transfers the mat sections to a supporting member 28 which preferably comprises a sheet of metal at least as wide as the mat and inclined downwardly in the outfeed direction at substantially the same angle as transfer belt 26.

Supporting member 28 may be mounted in any suitable manner, but as is illustrated in Figure 2, preferably is rigidly affixed to an angle iron 30 which extends transversely of the apparatus and is rigid to a pair of vertically disposed, perforated, supporting plates 32, stationed one on each side of the apparatus. Journalled in bearings 34, which are mounted within the perforations in plate 32, is a shaft 36 supported at each end by a standard 38 connected to the frame of the apparatus.

Means are provided for precisely adjusting the angle of pivotally mounted supporting member 28 with respect to the other elements of the apparatus. To this end at least one of plates 32 is provided with a longitudinal extension 39. This serves as a lever arm and has at its outer end a plurality of teeth engaging a worm 40 journalled in bearings 42, 44 which, in turn, are affixed to standard 38. It will be apparent that by rotating the shaft mounting worm 40, the angle of supporting member 28 may be varied by increments as desired.

Cooperating with transfer belt 26 and the pivotally mounted supporting member 28 is means for conveying the mats away therefrom for further processing. In the illustrated form the conveying means comprises an endless belt 50 stationed below Fourdrinier wire 16, transfer belt 26, and supporting member 28. It extends outwardly from the latter and is driven in the outfeed direction at a rate substantially the same as the rate of travel of both the Fourdrinier wire and the transfer belt.

Conveying belt 50 serves a three-fold function. First, as has been noted, it conveys the fibrous mat away from supporting member 28 for further treatment. Secondly, if the subsequent treatment is to be a pressing operation, it affords a means for placing below the mat one of the caul plates indicated at 52, 54 and which has dimensions substantially equal to those of the mat. This may be accomplished simply by placing the caul plates edge to edge on the upper end of conveyor belt 50. Then as each mat leaves supporting member 28 it is deposited upon the caul plate directly beneath and in registry with it.

An upper caul plate 56 then may be placed on top of the mat to form an assembly which may be introduced into a hot press for consolidation into a pressed board product. As is illustrated schematically, such an assembly may comprise the mat 58, sandwiched between a lower caul plate 60 and an upper caul plate 62, this entire assembly or an assembly including one or more venting screens, being placed between the lower platen 64 and the upper platen 66 of a suitable press.

The third function served by the conveying belt 50 comprises providing an opportunity, in cooperation with the supporting plate 28 from which it is spaced apart, for applying liquid to the underside of the mat efficiently and without disturbing or disarranging the mat. As is apparent particularly from Figures 2 and 3 this is accomplished by stationing a liquid applying means in this space, the liquid applying means being directed in the outfeed direction so that it applies liquid to the under surface of the mat as it transfers from supporting member 28 to conveying belt 50.

The form of the particular liquid applying means employed is widely variable depending upon such factors as the character of the liquid to be applied, its viscosity, its content of solids, etc. Thus one type of applying means

may be used where liquid water is to be applied to the mat; another where an aqueous solution of resin or inorganic salt is to be applied; a third where an organic solution of a solid material is to be applied; and a fourth, where an emulsion or a thixotropic colloidal suspension is to be applied.

The illustrated form of liquid applying means is designed particularly for applying water, aqueous solutions, or similar liquids to the mat. It comprises a plurality of spray heads 70, 72 and 74, spaced apart at suitable intervals and supported on a bracket 76. The bracket in turn is slidably mounted on guides 78, 80 so that the entire spray head assembly may be removed conveniently from the apparatus if desired. This permits the rapid servicing or adjustment of the spray heads. Each spray head is provided with a mixing chamber 82 which is fed with liquid through line 84 and with air or with other gas under pressure through line 86. If desired, the entire spray head assembly may be reciprocated by means of a crank 20 88.

Operation

The operation of the illustrated embodiment of the present invention is as follows:

Lignocellulose or other fiber is formed into a felt or mat on the forming wire 16 from felting head 10 assisted by suction box 18. The resulting mat then is partially consolidated by roll 22 and cut in sections by cut-off saws 24. These traverse transfer belt 26 and pass over the supporting plate 28, the angle of which is adjustable through worm 40.

As the mat sections travel over the transfer belt and the supporting plate their travel is paralleled by that of caul plates 52, 54 placed on an outfeed conveyor belt 50 stationed a spaced distance below the transfer belt and the support plate. Accordingly, as each mat section passes over the outfeed end of the supporting plate it is transferred to the caul plate immediately below. An upper caul plate then may be placed on top of the section and the assembly transferred to the hot press for consolidation into pressed fiber board.

Liquid is applied by means of spray heads 70, 72, 74 in predetermined quantity and at the selected rate to the under surface of each mat at the transfer point between support plate 28 and the caul plate carried by conveyor belt 50. This is accomplished without turning the mat over and consequently without disarranging its component fibers, or disturbing its surface. As a result there are obtained optimum control of the liquid applied; maximum development of the desired properties per unit amount of applied liquid; and the production of a consolidated product having maximum strength, uniform density, and surface characteristics which have been unimpaired by the application of the liquid. The liquid may be applied, furthermore, to continuously forming mats or sheets without substantial modification of the apparatus employed for their formation and conveyance. Also, if so desired, the upper surface of the mat may be coated with the same or with a different liquid at any convenient point between the consolidating roller and the point at which the upper caul is placed on the mat.

It is to be understood that the form of my invention herewith shown and described is to be taken as a preferred example of the same, and that various changes in the shape, size and arrangement of parts may be resorted to without departing from the spirit of my invention or the scope of the subjoined claims.

Having thus described my invention, I claim:

1. Apparatus for continuously applying liquids to the underside of a sheet of felted lignocellulose which comprises a supporting member inclined downwardly in the outfeed direction for supporting the sheet, means for moving the sheet across the supporting member at a predetermined rate, conveying means adapted to carry a caul plate a spaced distance below the supporting mem-

ber and extending outwardly on the outfeed side thereof, means connected to the conveying means for driving the same at a rate substantially equal to the rate of travel of the sheet and in the same direction, and liquid applying means stationed between and beneath the supporting member and the conveying means and directed toward the underside of the sheet as it traverses the space between the supporting member and the conveying means and is deposited on the caul plate carried thereby, said liquid applying means comprising at least one sprayhead, a bracket for supporting the sprayhead, means for slidably mounting the bracket on the underside of the supporting member, and means connected to the bracket for reciprocating same laterally with respect to the sheet.

2. Apparatus for continuously applying liquids to the underside of a sheet of felted lignocellulose which comprises a supporting member inclined downwardly in the outfeed direction for supporting the sheet, means for moving the sheet across the supporting member at a predetermined rate, conveying means adapted to carry a caul plate a spaced distance below the supporting member and extending outwardly on the outfeed side thereof, means connected to the conveying means for driving the

10

20

same at a rate substantially equal to the rate of travel of the sheet and in the same direction, and liquid applying means stationed between and beneath the supporting member and the conveying means and directed toward the underside of the sheet as it traverses the space between the supporting member and the conveying means and is deposited on the caul plate carried thereby, said liquid applying means comprising at least one sprayhead, a bracket mounting the sprayhead, and a pair of spaced-apart slides attached transversely to the underside of the supporting member and adapted to slidably receive the bracket therein thereby permitting lateral withdrawal of the bracket from the supporting member.
